UNITED STATES PATENT OFFICE.

ALFRED B. FOWLER, OF BEVERLY, MASSACHUSETTS, ASSIGNOR TO UNITED SHOE MACHINERY CORPORATION, OF PATERSON, NEW JERSEY, A CORPORATION OF NEW JERSEY.

LOCK-STITCH SEWING MACHINE.

Application filed December 7, 1922. Serial No. 605,383.

The present invention relates to lockstitch sewing machines, the stitch forming devices of which include a hook needle by which loops of needle thread are drawn through the work and a loop taker in the form of a shuttle or hook for passing a locking thread through the needle loops, which loop taker is necessarily located on the same side of the work as the hook needle. More particularly the invention relates to that class of hook needle lockstitch sewing machines which are not provided with a thread arm or other device to measure off between the needle and the work a sufficient amount of thread to supply one side of the needle loop as the needle retracts through the work after the thread has been laid in its hook. An example of this class of machines is the so-called "lockstitch McKay sewing machine" in which the shoe is supported during the sewing operation by a horn which extends inside of the shoe and which sews a seam passing through the shoe sole from the outside to the inside of the shoe. In machines of this type it has been found to be impracticable to use a thread arm or thread measuring device of any kind to supply thread for one side of the needle loop and, accordingly, where these machines have been provided with a take-up to set the stitch it has been necessary to use an extremely large needle as compared with the size of the thread in order to permit the thread to reeve through the hook of the needle during its retraction through the work. To avoid the use of a large needle in these machines, the shuttle has been utilized to set the stitch, and whether or not a take-up is embodied in the machine, at least a portion of the needle loop after being passed around the shuttle has been left projecting from the work so that the needle during its retracting stroke can be supplied with thread from this loop. With these machines in order to produce a satisfactory seam in the work on which they are designed to operate it is necessary to set the stitch against a thread lock and in a machine in which the stitch is set by the shuttle it has heretofore been necessary to open the lock during the action of the shuttle in setting the stitch so as to permit the shuttle to pull off thread from the supply for the next stitch. With this mode of operation irregularities in the posi-

tion of the lock of the stitch in the work are 55 bound to occur and also there is liability of injury to the thread as it is drawn through the lock at the instant the lock is opened.

The object of the present invention is to 60 eliminate the defects in the construction and operation of prior hook needle lockstitch machines which are not provided with a thread arm or other thread measuring device to 65 supply thread for one side of the needle loop and to provide a machine of this class which will operate to set the locks of the stitches accurately in the work without liability of breaking or injuring the thread, and with 70 this object in view the present invention contemplates the provision, in a machine of this class, of a thread handling device which cooperates with the other thread handling devices of the machine in such a manner as to permit the thread lock against which the 75 stitch is set to be opened and closed at points in the cycle of operation when the device which is used to set the stitch is not exerting a strain on the thread tending to pull the thread through the thread lock. By the provision of such a thread handling device 80 the various parts which are utilized in forming and setting the stitch can be constructed and arranged to operate in such a manner that one of said parts acts to set the stitch and another of said parts acts to 85 draw thread from the supply for the next stitch. The operations of setting the stitch and of drawing thread from the supply for the next stitch being thus separated the 90 thread can be manipulated with extreme accuracy, so that the lock of the stitch will always be drawn to the same location with 95 relation to the surface of the work and at the same time the use of a small needle is permitted and liability of injury to the 100 thread is eliminated.

In its broader aspects the invention contemplates the provision of any form of thread handling device which will cooperate 105 with the other parts to permit the desired mode of operation and contemplates utilizing any suitable parts for the setting of the stitch and for drawing thread from the supply for the next stitch. It is preferred, however, to use the shuttle to set the stitch, it being noted that the term "shuttle" as here used and as hereafter used in the claims is intended to include a hook or other

loop taking device by which the locking thread is passed through the loops of needle thread, and to embody in the machine another thread handling device in the form 5 of a pull-off which at a suitable point in the cycle of operations acts to pull from the supply the requisite amount of thread for use in forming the stitch. To adapt the machine for operation on work of varying 10 thickness or upon work of different thicknesses means are preferably provided controlled by the thickness of the work for varying the action of the pull-off. Also in order 15 to eliminate as far as possible the reeving of the thread around the materials being sewed the machine is preferably provided with a take-up acting to pull the needle loop from the shuttle partially back through the work.

The preferred form of the present invention is illustrated in the accompanying drawings as embodied in a lockstitch McKay shoe sewing machine, so much only of the machine being illustrated as is necessary for an understanding of the present invention. Figure 1 is a view in side elevation of the machine; Figure 2 is a detail view showing in front elevation and partially in section certain parts of the machine and particularly the pull-off mechanism and 20 its connection with the presser foot; Figure 3 is a detail sectional plan view of the pull-off mechanism and thread locks; Figure 4 is a view in side elevation, partly in section, of the mechanism illustrated in Figure 3; Figure 5 is a detail view in side elevation of the mechanism for actuating the thread locks; and Figures 6, 7 and 8 are diagrammatic views illustrating the operation of the thread handling devices of the machine in 25 forming and setting a stitch.

Except as hereinafter described the machine illustrated in the drawings is the same in construction and mode of operation as the lockstitch McKay shoe sewing machine illustrated and described in the patent to Goddard and Jerram, No. 1,353,827, dated September 28, 1920. Referring to Figures 1 and 2, the straight hook needle of the machine is indicated at 9, the shuttle at 10, the presser foot at 11, the feed point at 12, the shoe supporting horn at 13, and the whirl which lays the thread in the hook of the needle at 14. The needle, presser foot and feed point are actuated from a horizontal cam shaft driven 30 through bevelled gears 15 and 16 from a vertical shaft 17, and the shuttle and whirl are driven through connections from the vertical shaft 17, as in the machine of the Goddard and Jerram patent.

The illustrated machine is provided with a thread lock against which the stitch is set by the shuttle, which lock corresponds to the thread lock of the machine of the Goddard and Jerram patent. To permit this lock 35 to be opened and closed at times in the

cycle when there is no strain on the thread tending to pull it through the lock, the illustrated machine is provided with a second thread lock located between the first mentioned lock and the work and with a pull-off device operating in connection with the lock to pull off from the supply the amount of thread needed in the formation of a stitch. The thread lock against which the stitch is set comprises two members consisting respectively of a spring pressed plunger 18 mounted upon a lever 19 and a fixed clamping plate 20 mounted upon a bracket 21 secured to the frame of the machine. This thread lock may be termed "the rear thread lock." 40 The other thread lock which may be termed "the front thread lock" comprises two members consisting of a spring pressed plunger 22 mounted in the lever 19 and a fixed clamping plate 23 mounted in the bracket 21. The lever 19 is pivotally mounted midway between the plungers 18 and 22 upon the bracket 21 and is provided with an arm having a pin and slot engagement with the forward end of a lever 24, the rear end of which is engaged by a cam groove in the barrel member 25 on the vertical shaft 17. With this construction, as the lever 19 is rocked, one of the thread clamps is opened and the other closed. The pull-off device is located 45 between the two thread clamps and comprises a fork 26 across which the thread extends as it passes from the supply through the two thread clamps, and a pull-off arm 27, the end of which extends over the thread above the two arms of the fork 26 and which, as the end of the arm is moved downwardly, is adapted to bend the thread downwardly between the two arms of the fork. The arm 27 forms part of a lever, the rear end of which is engaged by a cam in the barrel member 25. To cause the pull-off device to pull off an amount of thread varying with the thickness of the work the fork 26 is formed at the upper end of a vertical bar 50 mounted to slide in the bracket 21 and connected to the presser foot carrying bar of the machine by a lever 29, a vertical connecting rod 30 and a lever 31. An adjustable bolt and slot connection between the connecting rod 30 and the lever 29 permits an adjustment of the parts to cause the desired variation in the amount of thread pulled off upon a variation in the thickness of the work.

In addition to the thread handling parts above described the illustrated machine is also provided with cam actuated take-up levers 32 and 33 carrying take-up rolls 34 and 35 which are arranged to operate in substantially the same manner as the take-up levers of the machine of the Goddard and Jerram patent.

The construction of the thread handling devices of the illustrated machine being as above described their operation in forming

and setting a stitch is as follows:—Starting with the needle at the limit of its upward stroke the needle descends through the work so as to bring its hook into position to receive the thread which is laid therein by the whirl in the tip of the horn. At this time in the cycle the parts are in substantially the position indicated in Figure 6, the take-up levers being separated to their greatest extent, the front thread lock being closed and the rear thread lock being opened. At this point in the operation it will be noted that the loop of needle thread which has just been passed around the shuttle has been pulled only partially back through the work. After receiving the thread in its hook the needle retracts to the position indicated in Figure 7 and during this movement thread for the work side of the loop drawn up by the needle is supplied from the preceding loop so that there is no rendering of the thread through the hook of the needle and the needle can pass through the work without any danger of breaking the thread. During the upward movement of the needle, thread for the supply side of the loop is given up by the take-up levers which approach each other. At some point in the cycle of operation while the front thread lock remains closed the pull-off is actuated to pull thread from the supply through the rear thread lock, as indicated in Figure 6. As the needle nears the limit of its upward stroke the loop is engaged by the shuttle and extended to the position indicated in Figure 8, and prior to the time when the parts reach this point in the cycle the front thread lock is opened and the rear thread lock is closed so that the thread which has been pulled off by the take-up is permitted to pass through the front thread lock and the thread is drawn tight between the top of the shuttle and the rear thread lock. The amount of thread which has been drawn off by the take-up is just sufficient to cause a stitch setting strain to be exerted upon the thread as the loop of needle thread passes over the top of the shuttle so as to set the lock of the stitch in the required position with relation to the surface of the work. After the stitch is set the take-up is actuated to draw the loop from the shuttle partially back through the work to the position indicated in Figure 6, and at some time after the thread is relieved of the stitch setting pull of the shuttle the rear thread lock is opened and the front thread lock is closed.

The nature and scope of the present in-

vention having been indicated and the preferred embodiment of the invention having been specifically described, what is claimed is:—

1. A lockstitch sewing machine having, in combination, stitch forming and setting devices including a hook needle operating during its retraction to draw thread from the preceding needle loop, a shuttle, a thread lock against which the stitch is set, and a thread handling device cooperating with said needle, shuttle and thread lock to permit the thread lock to be opened and closed while the thread is relieved of strain tending to pull it through the lock.

2. A lockstitch sewing machine having, in combination, stitch forming and setting devices including a hook needle, a shuttle acting to set the stitch, a thread lock against which the stitch is set, a pull-off, and means for varying the action of the pull-off to compensate for different thicknesses of work.

3. A lockstitch sewing machine having, in combination, stitch forming and setting devices including a hook needle, a take-up acting to pull the needle loop from the shuttle partially back through the work, a shuttle acting to set the stitch, a thread lock against which the stitch is set, a pull-off, and means for varying the action of the pull-off to compensate for different thicknesses of work.

4. A lockstitch sewing machine having, in combination, stitch forming and setting devices including a hook needle operating during its retraction to draw thread from the preceding needle loop, a shuttle, a thread lock against which the stitch is set, a pull-off, and means for varying the action of the pull-off to compensate for different thicknesses of work.

5. A lockstitch sewing machine having, in combination, stitch forming and setting devices including a hook needle operating during its retraction to draw thread from the preceding needle loop, a shuttle, a thread lock against which the stitch is set, a thread handling device cooperating with said needle, shuttle and thread lock to permit the thread lock to be opened and closed while the thread is relieved of strain tending to pull it through the lock, and means for actuating the needle, shuttle, thread lock and thread handling device to cause one of said parts to set the stitch and another of said parts to draw thread from the supply.

ALFRED B. FOWLER.
